WORK HOLDER

Tideman M. Lilleberg, Chicago, Ill., assignor to
The Nye Tool & Machine Works, a corpora-
tion of Illinois

Application March 9, 1939, Serial No. 260,846

17 Claims. (Cl. 10—107)

My invention relates to work holders of the type having jaws to receive between them the work to be held, such as for example a pipe to be threaded.

5 One of my objects is to provide a novel, simple, and positively operating construction of holder of the type referred to.

Another object is to provide a construction of holder which may be quickly and easily operated to clamp the work therein in properly centered 10 position.

Another object is to provide a construction of holder which may be quickly and easily operated to clamp the work therein regardless of its cross 15 sectional size within certain limits.

Another object is to provide a construction of work holder whereby through a single drive element work, regardless of its cross sectional dimension, within certain limits, may be rigidly 20 clamped in the proper centered position; and other objects as will be manifest from the following description.

Referring to the accompanying drawings:

Figure 1 is a view in end elevation, partly sec- 25 tional, of pipe threading mechanism comprising a work holder constituting one of the forms in which my invention may be embodied.

Figure 2 is a section taken at the line 2 on Fig. 1 and viewed in the direction of the arrow.

30 Figure 3 is a fragmentary view like Fig. 1 showing in elevation the parts illustrated in section in Fig. 1 and with other parts sectioned.

Figure 4 is a fragmentary sectional view taken at the line 4 on Fig. 3 and viewed in the direction 35 of the arrow.

Figure 5 is a sectional view of certain of the parts shown in Figs. 1-4.

Figure 6 is a view in elevation of one of the jaws of the device.

40 Figure 7 is a plan view of certain of the parts of the structure shown in Fig. 5, these parts being viewed at the line 7 in this figure.

Figure 8 is an end view of the jaw of Fig. 6.

45 Figure 9 is a fragmentary view of the structure of Fig. 5 viewing it in the direction of the arrow 9 in this figure.

Figure 10 is a fragmentary sectional view of a jaw-equipped portion of the device of Figs. 1 and 2.

50 Figure 11 is a view in side elevation, partly sectional, of a gear-equipped sleeve forming a part of the structure shown in Fig. 10.

Figure 12 is a view like Fig. 1 of another form of structure embodying my invention.

55 Figure 13 is a section taken at the line 13 on

Fig. 12 and viewed in the direction of the arrow.

Figure 14 is a view like Fig. 1 of still another form of structure embodying my invention; and

Figure 15, a section taken at the line 15 on Fig. 14 and viewed in the direction of the arrow.

Referring to the construction shown in Figs. 1-11, inclusive, it comprises a ring member 16 formed of sections 17 and 18 having registering annular channels forming an annular recess 19, the sections 17 and 18 being shown as secured together as by screws 20.

The section 18 has arms one of which is shown at 21, extending therefrom lengthwise of the device and connected with a ring portion 22 internally threaded at 23 at which it is adapted to have threaded connection, in accordance with common practice, with a carrier 24 (a portion only of which is shown) for the thread-cutting chasers (not shown) for cutting a thread on a pipe, such as the pipe 25 rigidly clamped, against rotation, in the work holder of which the rings 16 and 22 are parts.

The ring section 17 is provided with a plurality of radially movable jaws shown as three in number and designated at 26, 27 and 28, and substantially equidistantly spaced around the ring 16.

20 The jaws 26-28 are slidable in radial openings in the ring section 17, each being of non-circular cross sectional shape as shown of one 30 of these openings at 29 in Figs. 5 and 9. The jaws 26-28 at their inner end portions are of a cross sectional shape to slidingly fit the openings in the ring section 17, having opposite flat sides as represented at 30, whereby these jaws are 35 held against rotation.

The end faces of the jaws 26-28 have cross grooves 31 and are chamfered as shown at 32 to form biting edges.

40 The jaws 26 and 27 are externally threaded at their outer ends as represented at 33 at which portions they screw into the internal threads of rotatable sleeves 34 surrounding them and located in similar recesses in the ring section 17, the recess for the one of the sleeves 34 surround- 45 ing the jaw 26, being shown at 35.

The inner ends of the sleeves 34 are provided with similar pinions, the pinion for the sleeve 34 surrounding the jaw 26, being shown at 36, bushings 37 screwed into the threaded outer ends 50 of the recesses referred to, in conjunction with the end walls of these recesses, holding the sleeves 34 against longitudinal movement.

The pinions on the sleeves 34 mesh with a ring gear 38 rotatably confined in the recess 19, 55

whereby when the gear 38 is rotated, as herein-after described, both of the sleeves 34 are rotated, and, through their threaded connection with the jaws 26 and 27, simultaneously move these jaws in or out at the same speed, depending on the direction in which the gear 38 is rotated.

The jaw 28 is externally threaded at its outer end as shown at 39 at which portion it engages an internal thread 40 on a rotatable sleeve 41 extending at its inner end into a recess 42 in the ring section 17 at the opening 29, the inner end of the sleeve 41 having an external annular flange 43. Surrounding the sleeve 41 is a rotatable sleeve 44 annularly recessed at 45 to receive the flange 43 and having a pinion 46 thereon identical with the pinions on the sleeves 34. A bushing 47 screwed into the recess 42, in conjunction with the end wall of this recess, prevents lengthwise movement of the sleeve 44 and such movement of the sleeve 41 is prevented by the overlapping of the flange 43 with the inner end of the sleeve 44.

Surrounding the outer end of the sleeve 41 and secured thereto, as by rivets 48, is a sleeve 49 having an expanded end 50 surrounding the outer end of the sleeve 44, the sleeve 50 having an arcuate recess 51 for a purpose hereinafter explained.

30 Located between the expanded end 50 of the sleeve 49 and the sleeve 41, is a coil spring 52, under tension tending to uncoil, one end thereof, represented at 53, being connected with the sleeve 49 and its other end 54 connected with the gear sleeve 44.

The gear sleeve 44 is provided with a pin 55 which extends into the arcuate recess 51.

The sleeves 41 and 49 which form a single rotatable unit, are provided with handle means by which to rotate them, as for example the sliding bar handle shown at 50a which is slidable crosswise of these sleeves in openings provided therein.

In the use of the work holder the operator rotates the sleeves 41 and 49 in counterclockwise direction in Fig. 4 to withdraw the jaws 26, 27 and 28 sufficiently to permit the pipe 25 to be slid into the space between these jaws. The jaw 28 is moved outwardly by the threaded engagement of the sleeve 41 with the jaw and the jaws 26 and 27 are similarly moved simultaneously with the jaw 28 by the rotation of the gear sleeve 44 through the engagement of the end wall 51a of the slot 51 with the pin 55, the gear sleeve 44 in rotating driving the ring gear 38 which latter, in turn, rotates the sleeves 34 which through their threaded connection with the jaws 26 and 27 move the latter outwardly.

To clamp the pipe in place, the operator rotates the sleeves 41 and 49 in clockwise direction in Fig. 4. The jaw 28 is moved inwardly by the rotation of the sleeve 41 and the jaws 26 and 27 are simultaneously moved inwardly with the jaw 28 through the medium of the sleeves 34, ring gear 38, gear sleeve 44, and spring 52, the spring 52 being under such tension in the normal position of the parts that through it the jaws 26 and 27 move simultaneously inward, with the jaw 28, it being understood that the drive of the gear sleeve 44 is through the medium of this spring. All of the jaws continue their simultaneous inward movement until they engage the pipe 25 under a pressure exceeding the tension of the spring 52. The operator continues to rotate the sleeves 41 and 49 throughout a partial revolution thus causing the jaw 28 to continue to move in-

wardly and effect tight clamping of the pipe within the holder. It will be understood that in this final rotative movement of the sleeves 41 and 49 the spring 52, because of its connection with the gear sleeve 44, which latter has become stationary, is increased in tension, the recess 51 permitting the sleeves 41 and 49 to thus continue their rotation after the movement of the gear sleeve 44 has been arrested. The threaded connection between the jaw 39 and the sleeve 41 is sufficiently fine as to prevent the jaw 28 from moving outwardly after having once been set in the clamped position stated.

The initial tensioning of the spring 52 determines the pressure exerted by the jaws 26, 27 and 28 against the pipe in their simultaneous inward movement, the final inward movement of the jaw 28, independently of the jaws 26 and 27, effecting the final clamping of the pipe in the work holder.

To release the pipe from the holder the operator rotates the sleeves 41 and 49 in counterclockwise direction in Fig. 4, the initial movement of these sleeves moving the jaw 28 outwardly until the pin 55 is engaged by the end wall 51a of the slot 51, whereupon all of the jaws move simultaneously outward.

In the particular construction shown means are provided for holding the work in the holder in such offset-center position, if desired, as to produce a so-called crooked thread on the pipe when operated on by the thread-cutting mechanism. These means comprise a jaw member 56 in the form of a screw threaded in the jaw 26 which in this instance is of tubular form. When a crooked thread is to be produced the jaw member 56 is preliminarily screwed inwardly the desired distance beyond the inner end of the jaw 26 for causing the pipe to be clamped in the desired off center position when the several jaws of the device are moved inwardly by the mechanism above described.

The construction shown in Figs. 12 and 13 is the same as that shown in Figs. 1-11, inclusive, except for the means which operate the ring gear 38 (to actuate the jaws 26 and 27) and the final pressure applying jaw (corresponding to the jaw 28) and its operating means.

In this construction the final pressure applying jaw represented at 57 is externally threaded at its inner end as represented at 58 at which portion it screws in a threaded radial opening 59 in the ring section 17, its outer end being equipped with a handle 60 as in the case of the sleeves 41 and 49 of the construction shown in Figs. 1-11.

The ring section 17 contains a recess 61 at the opening 59 in which a rotatable sleeve 62 is located. This sleeve which surrounds, and is spaced from, the inner end of the jaw 57, has a pinion 63 which corresponds to the pinions 36 associated with the jaws 26 and 27, and meshes with the ring gear through which the jaws 26 and 27 are driven. A bushing 64 screwed into the recess 61 serves the same purpose as the bushings 37.

A coil spring 65, under tension tending to uncoil, is located in the space between the jaw 57 and the gear sleeve 62, one end 66 of this spring being connected with the gear sleeve 62 and its other end connected with a collar 67 surrounding the jaw 57 and located in the gear sleeve 62. A washer 68 holds the collar 67 in position in the sleeve.

The jaw 57 and the collar 67 are connected to

gether to rotate as a unit, but permit of lengthwise movement of this jaw relative to the collar, by a key 69 on the collar and extending into a longitudinal groove 70 in the jaw 57.

5 The collar 67 has a radial pin 71 which extends into an arcuate slot 72 in the gear sleeve 62. The spring 65 is normally under tension tending to uncoil, in which condition the pin 71 is in engagement with the end wall 73 of the slot 72.

10 To condition the holder to receive the pipe 25, the operator rotates the jaw 57 in counterclockwise direction in Fig. 13 to withdraw the jaws 26, 27 and 57 sufficiently to permit the pipe to be slid into the space between these jaws. The 15 jaw 57 in this movement moves outwardly by reason of its rotation in the threaded opening 59; the jaws 26 and 27 moving outwardly simultaneously with the jaw 57, by the pin 71 on the rotating collar 67 (rotated by its key connection 20 with the jaw 57) abutting the end wall 73 of the slot 72.

To clamp the pipe in place, the operator rotates the jaw 57 in clockwise direction in Fig. 13. The jaw 57 moves inwardly by reason of its 25 threaded connection with the ring section 17 and the jaws 26 and 27 are simultaneously moved inwardly with the jaw 57 through the medium of the sleeves 34, the ring gear meshing therewith, the gear sleeve 62 and spring 65, the spring 65 being under such tension in the normal position of the parts that through it the jaws 26 and 27 move simultaneously inward with the jaw 57. All of the jaws continue their simultaneous inward movement until they engage the pipe 25 under a pressure exceeding the tension of the 35 spring 65. The operator continues to rotate the jaw 57 throughout a partial revolution thus causing this jaw to continue to move inwardly and effect clamping of the pipe within the holder, 40 the parts assuming the positions shown in Figs. 12 and 13. In this final rotative movement of the jaw 57 the spring 65, because of its connection with the gear sleeve 62, which latter has become stationary, is increased in tension, the 45 slot 72 permitting the jaw 57 to thus continue its rotation after the movement of the gear sleeve 62 has been arrested in which movement of the jaw 57 the pin 71 moves away from the end wall 73 of the slot.

50 The pipe is released from the holder by reversely rotating the jaw 57, carrying the collar 67 with it, the initial movement of the jaw 57 causing the latter to move outwardly until the pin 71 engages the end wall 73 of the slot 72, 55 whereupon all of the jaws move simultaneously outward.

The construction shown in Figs. 14 and 15 is also the same as that shown in Figs. 1-11, inclusive, except for the means which operate the 60 ring gear 28 (to actuate the jaws 26 and 27) and the final pressure applying jaw (corresponding to the jaw 28) and its operating means.

In this construction I provide, in addition to the jaws 26 and 27, a tubular jaw 74 externally threaded at 75 at which it engages an internal thread 76 in a radial opening 77 in the ring section 17, the tubular jaw 74 having a longitudinal key-way 78 and being internally threaded as represented at 79.

70 The ring section 17 contains a recess 80 at the opening 77 in which a rotatable sleeve 81 is located. This sleeve, which surrounds, and is spaced from, the inner end of the tubular jaw 74, has a pinion 82 which corresponds to the 75 pinions 36 associated with the jaws 26 and 27

and meshes with the ring gear through which the jaws 26 and 27 are driven. A bushing 83 screwed into the recess 80 serves the same purpose as the bushings 37.

The tubular jaw 74 and the gear sleeve 81 are 5 connected together to rotate as a unit, but permitting of longitudinal movement of the jaw 74 relative to this sleeve, by a key 84 on the interior of the gear sleeve 81 and extending into the key-way 78.

10 Threaded in the jaw 74 is a supplemental jaw 85, its outer end being equipped with a handle 86 as in the case of the sleeves 41 and 49 of the construction shown in Figs. 1-11.

A coil spring 87 under tension tending to uncoil, is located in the space between the jaw 85 and the gear sleeve 81, one end 88 of this spring being connected with the gear sleeve 81 and its other end 89 connected with a collar 90 surrounding the jaw 85 and located in the gear sleeve 81. A washer 91 holds the collar 90 in position in the sleeve.

The jaw 85 and the collar 90 are connected together to rotate as a unit, but to permit of lengthwise movement of this jaw relative to the 25 collar, by a key 92 on the collar and extending into a longitudinal groove 93 in the jaw 85.

The collar 90 has a radial pin 94 which extends into an arcuate slot 95 in the gear sleeve 30 81. The spring 87 is normally under tension 30 tending to uncoil, in which condition the pin 94 is in engagement with the end wall 96 of the slot 95.

To condition the holder to receive the pipe 25, the operator rotates the jaw 85 in counterclockwise direction in Fig. 15 to withdraw the jaws 26, 27 and 74 (the jaw 85 being in withdrawn position) sufficiently to permit the pipe to be slid into place between these jaws. The pin 94 being in engagement with the end wall 96 of the 40 slot 95, the gear sleeve 81 and the gear sleeves 34 of the jaws 26 and 27 are rotated, moving all of the jaws outwardly, the key and slot connection 84, 78, between the gear sleeve 81 and the jaw 74 rotating the jaw 74 which 45 latter by reason of its threaded engagement with the threaded opening 75 in the ring flange 17 moves outwardly at the same speed as the jaws 26 and 27.

To clamp the pipe in place the operator rotates the jaw 85 in clockwise direction in Fig. 15. This causes the gear sleeve 81 to be rotated through the medium of the spring 87 which, through the medium of the ring gear and the gear sleeves 34, moves the jaws 26 and 27 inwardly and through the key and slot connection 84, 87, rotates the jaw 74 thereby causing this jaw to screw inwardly in the opening 75 simultaneously with, and at the same speed as, the jaws 26 and 27; it being noted that the jaw 85 advances inwardly with the jaw 74 turning with the latter as a unit. The jaws 26, 27, 74 and 85 continue their simultaneous inward movement until the jaws 26, 27 and 74 engage the pipe 25 under a pressure exceeding the tension of the spring 65.

81 The operator continues to rotate the jaw 85 throughout a partial revolution thus causing this jaw to continue to move inwardly, as inward movement of the jaw 74 has been arrested, for effecting clamping of the pipe within the holder, the parts assuming the position in Figs. 14 and 15. In this final rotative movement of the jaw 85 the spring 87, because of its connection with the gear sleeve 81, which latter has become stationary, is increased in tension, the slot 95 per-

mitting the jaw 85 to thus continue its rotation after the movement of the gear sleeve 81 has been arrested, in which movement of the jaw 85 the pin 94 moves away from the end wall 96 of the slot 95.

The pipe is released from the holder by reversely rotating the jaw 85, carrying the collar 90 with it, the initial movement of the jaw 85 causing the latter to move outwardly by reason 10 of its threaded connection with the tubular jaw 74 which is stationary at this time, until the pin 94 engages the end wall 96 of the slot 95, whereupon the jaws 26, 27 and 74 move outwardly.

As will be understood from the foregoing, the 15 operation of tightening the clamping jaws against the work introduced into the holder is exceedingly simple requiring the application of force to a single member only for properly centering the work, regardless of its cross sectional dimension within certain limits and finally clamping it in such centered position, the first portion of the movement of the means engaged by the operator for actuating the jaws serving to center the pipe in the holder, and the latter part of the movement of these means, continued in the same direction, exerting the final rigid clamping effect upon the work.

While I have illustrated and described certain constructions embodying my invention I do 30 not wish to be understood as intending to limit the invention thereto as the same may be variously modified and altered and the invention embodied in other forms of structure without departing from the spirit of the invention.

35. What I claim as new and desire to secure by Letters Patent, is:

1. A work holder having a plurality of work-engaging jaws, and means having a single actuating device operating when actuated to move all of said jaws and comprising yieldable means by which certain only of said jaws are operated inwardly, whereby when said device is actuated all of said jaws move inwardly until resisted by the work, whereupon said yieldable means yield and a predetermined one of the jaws continues its inward movement.

2. A work holder having a plurality of work-engaging jaws, a single drive element and means actuated by said element operating when actuated to move all of said jaws and comprising yieldable means by which certain only of said jaws are operated inwardly, whereby when said element is actuated all of said jaws move inwardly until resisted by the work, whereupon said yieldable means yield and a predetermined one of the jaws continues its inward movement.

3. A work holder having a plurality of work-engaging jaws, means operating when actuated to move certain of said jaws, a single drive element, yieldable means by which said drive element drives said first-named means for moving said last-referred-to jaws inwardly, and means operated by said drive element for moving another predetermined one of said jaws inwardly with the others thereof and continuing the inward movement of said jaw upon the yielding of said yieldable means.

4. A work holder having a plurality of work-engaging jaws, gear mechanism operating, when actuated, to move certain of said jaws, a single drive element, yieldable means by which said drive element drives said mechanism for moving said last-referred-to jaws inwardly, and means operated by said drive element for moving another predetermined one of said jaws inwardly

with the others thereof and continuing the inward movement of said jaw upon the yielding of said yieldable means.

5. A work holder having a plurality of work-engaging jaws, a threaded rotatable sleeve with 5 which one of said jaws has threaded engagement, a spring encircling said sleeve, a gear member, said spring being connected with said rotatable sleeve and said gear member, and means operated by said gear member for moving the others of 10 said jaws.

6. A work holder having a plurality of work-engaging jaws, a threaded rotatable sleeve with which one of said jaws has threaded engagement, a spring encircling said sleeve, a gear member 15 encircling said rotatable sleeve, a second sleeve rotatable with said rotatable sleeve and encircling said gear member, said spring being connected with said rotatable sleeve and said gear member, said second sleeve having an elongated 20 circumferential recess, a pin on said gear member extending into said recess, said spring being under tension, and means operated by said gear member for moving the others of said jaws.

7. A work holder having a plurality of work- 25 engaging jaws, a single drive element, a rigid drive connection between said element and one of said jaws, and a yieldable drive connection between said element and the other of said jaws permitting said element to be moved and actuate 30 the one of said jaws with which it has rigid drive connection without moving said other jaws when movement of said other jaws is resisted by the work.

8. A work holder having a plurality of work- 35 engaging jaws one of which has threaded connection with a stationary part of the holder and to which driving force is applied for moving all of said jaws, a collar on said last-referred-to jaw keyed thereto to be driven when this jaw is 40 rotated but relative to which this jaw is longitudinally movable, a spring engaging said collar, and means driven by said spring upon rotating said collar for moving the others of said jaws.

9. A work holder having a plurality of work- 45 engaging jaws one of which has threaded connection with a stationary part of the holder and to which driving force is applied for moving all of said jaws, a collar on said last-referred-to jaw keyed thereto to be driven when this jaw is 50 rotated but relative to which this jaw is longitudinally movable, a spring engaging said collar, means driven by said spring upon rotating said collar for moving the others of said jaws, said means having an elongated recess and a pin on said 55 collar extending into said recess, said spring being under tension.

10. A work holder having a plurality of work-engaging jaws one of which has threaded connection with a stationary part of the holder and to 60 which driving force is applied for moving all of said jaws, a collar on said last-referred-to jaw keyed thereto to be driven when this jaw is rotated but relative to which this jaw is longitudinally movable, a spring engaging said collar, a 65 gear member engaging said spring, and means driven by said gear member, upon rotating said collar, for moving the others of said jaws.

11. A work holder having a plurality of work-engaging jaws one of which has threaded connection with a stationary part of the holder and to which driving force is applied for moving all of said jaws, a collar on said last-referred-to jaw keyed thereto to be driven when this jaw is rotated but relative to which this jaw is longitudinally 75

movable, a spring engaging said collar, a gear member engaging said spring, means driven by said gear member, upon rotating said collar, for moving the others of said jaws, said gear member having an elongated recess and a pin on said collar extending into said recess, said spring being under tension.

12. A work holder having a plurality of work-engaging jaws, a drive element, yieldable means between said jaws and said driving element actuated by said element for moving all of said jaws to engage the work, said drive element having a jaw portion for engaging the work, and means whereby movement of said drive element after said yieldable means yield causes said last-named jaw to move against the work.

13. A work holder having a plurality of work-engaging jaws one of which has threaded engagement with a stationary part of the holder and is hollow with an internal thread, a rotatable drive element in said hollow jaw and having a work-engaging portion and a threaded portion at which it engages said internal thread, and yieldable means between said jaws and said drive element actuated by said element for moving all of said jaws, said hollow jaw being movable lengthwise relative to said means.

14. A work holder having a plurality of work-engaging jaws one of which has threaded engagement with a stationary part of the holder and is hollow with an internal thread, a rotatable drive element in said hollow jaw and having a work-engaging portion and a threaded portion at which

it engages said internal thread, a gear member having sliding key connection with said hollow jaw, yieldable means between said gear member and said drive element by which said gear member is rotated, and means actuated by said gear member for operating the others of said jaws.

15. A work holder having a plurality of work-engaging jaws and means having a single actuating device operating during a portion of the movement of said device to cause said jaws to engage the work and in the continuing movement of said means to cause clamping pressure to be initially applied at a predetermined point on one side of the work.

16. A work holder having a single drive element terminating in a work holding jaw, other work holding jaws and a yieldable drive connection between said element and said other jaws permitting said element to be moved and move said first-named jaw without moving said other 20 jaws when movement of said other jaws is resisted by the work.

17. A work holder having a single drive element terminating in a work holding jaw, other work holding jaws, a member having drive connection with said element and relative to which said element is longitudinally movable, and a yieldable drive connection between said member and the others of said jaws permitting said element to be moved and move said first-named jaw 30 without moving said other jaws when movement of said other jaws is resisted by the work.

TIDEMAN M. LILLEBERG.
